[57] CLAIM

The ornamental design for a jewelry display prop, as
shown and described.

DESCRIPTION

FIG. 1 is a perspective view of a jewelry display prop
showing my new design; the broken line showing of an
insert pad is for illustrative purposes only;

FIG. 2 is a top plan view thereof;

FIG. 3 is a bottom plan view thereof;

FIG. 4 is a front elevational view thereof;

FIG. 5 is a rear elevational view thereof;

FIG. 6 is a left end elevational view thereof;

FIG. 7 is a right end elevational view thereof;

FIG. 8 is a perspective view of a second embodiment of
the jewelry display prop shown in FIG. 1; the broken
line showing of an insert pad is for illustrative purposes
only;

FIG. 9 is a top plan view thereof;

FIG. 10 is a bottom plan view thereof;

FIG. 11 is a front elevational view thereof;

FIG. 12 is a rear elevational view thereof;

FIG. 13 is a left end elevational view thereof; and

FIG. 14 is a right end elevational view thereof.
